UNITED STATES PATENT OFFICE.

JAMES W. FOX, OF JOLIET, ILLINOIS.

FLANGE-OILER.

1,315,487.

Specification of Letters Patent.

Patented Sept. 9, 1919.

Application filed April 1, 1918. Serial No. 225,984.

To all whom it may concern:

Be it known that I, JAMES W. Fox, a citizen of the United States, residing at Joliet, in the county of Will and State of Illinois, 5 have invented certain new and useful Improvements in Flange-Oilers, of which the following is a specification.

My invention relates to flange oilers for locomotives. One object of this invention is 10 to maintain lubricated in a novel and improved manner the flange of a wheel.

Another object is the production of means for supporting the lubricator yieldingly with respect to the locomotive frame.

15 Another object is to improve flange lubricators for successful commercial use.

These and other objects are accomplished by providing an oil container adapted for connection to the frame of a locomotive 20 preferably by a spring strap and a novel valve, the stem of which is in engagement with the flange of a wheel.

By reference to the drawings the above recited and other objects will be apparent, 25 wherein—

Figure 1 is an elevation of the preferred embodiment of an oiler on the frame of the wheel, a fragmentary portion of a wheel and frame being shown.

30 Fig. 2 is a view of the device looking at the right hand end of Fig. 1.

Fig. 3 is a vertical section through the preferred embodiment of my invention, the parts being slightly enlarged.

35 Fig. 4 is a vertical section taken at 90 degrees to the section in Fig. 3.

Fig. 5 is a vertical section of a fragmentary portion of the casing showing the preferred arrangement of the valve for controlling the oil outlet.

40 Fig. 6 is a section on line 6—6 of Fig. 4, and

Fig. 7 is a section on line 7—7 of Fig. 3.

In the drawings, a portion 10 of a locomotive side frame is shown, the same being 45 supported on wheels 11, a portion of one of which is shown in outline. The oiler embodying the preferred form of my invention comprises an oil container 12 preferably 50 cylindrical and formed of pliable material such as a piece of hose and is supported on a U-shaped spring stirrup 13, one arm 13^b of which is suitably connected at 14 to the casing 12. The other arm 13^a of the stirrup 55 is somewhat longer than the arm 13^b and is provided with a strap 15 adapted to extend

around a portion of the frame 10 of the locomotive, as best seen in Fig. 2. The strap 15 is secured to the side 13^a of the stirrup by bolts or other suitable fastenings. By 60 this arrangement it will be noted that the oiler may be easily applied to or removed from the engine frame and may be adjusted to frames of various sizes. The resilient connection permits the lateral movement of 65 the oil container 12 with respect to the wheel to compensate for any play between the wheels and the frame which may occur due to irregularities. As a cover for the casing I provide a member 23 having an upturned 70 slide 24 adapted to fit the arm 13^b of the spring stirrup 13. Normally the cover 23 is as shown, resting on top of the casing 12 and closing the interior thereof.

It is essential in an oiler of the type described that means be provided to feed the oil to the wheel especially when the locomotive meets a curve in the track, the purpose being to oil the flanges of the wheels and to reduce friction between the rails and 80 the flanges. The arrangement which I prefer to employ for the control of the oil comprises preferably a wooden block 16 mounted in the lower portion of the casing 12 and having a central aperture 17 therethrough 85 serving as a valve opening and a bolt 18 therein, as a valve. This bolt 18 has the usual head 18^a and the threaded portion 19. The aperture 17 through the block 16 is made slightly larger than the diameter of 90 the bolt employed as a valve. It will be seen that the bolt 18 is supported by the head 18^a and because of the enlarged aperture 17, is permitted to be displaced bodily within the limits of the sizes of the apertures, or, in 95 other words, to oscillate with the head of the bolt as a center.

As shown in Figs. 1 and 2, the device is mounted on the frame 10 so that the end of the bolt engages the surface of the wheel 100 preferably at or near the flange. Because of the loose mounting of the bolt within the casing 12 and the flexibility of the casing itself, any movement of the wheel relatively to the frame 10 will impart movement to the 105 bolt 18 and the casing 12. This movement permits the oil within the casing 12 to flow down the bolt and be deposited on the wheel. Because of the threads in the bolt the oil is led directly to the wheel and is not lost as 110 in the case where there is no leader from the oil reservoir to the wheel. Furthermore, the

movement of the bolt may be controlled by means of the lock nut 21 engaging the threads at the upper portion of the bolt and mounted on the bottom of the casing 12 underneath the block 16. The block 16 is provided with an elongated slot 22 to receive the lock nut 21. Thus, it will be observed by moving the lock nut 21 upwardly or downwardly the bolt may be held within the block 16 as tightly or as loosely as desired, the adjustability depending upon the amount of oil to be fed to the wheel, the bolt being oscillated continually while the locomotive is in motion.

15 The device operates to lubricate the wheel flange in the following manner: The parts being mounted as shown in Figs. 1 and 2 with the lower end of the bolt arranged to engage the surface of the wheel or flange as 20 may be desired, so that when relative movement between the wheels 11 and the frame 10 occurs, which happens whenever a joint in the tracks is struck by the wheels or when the locomotive is rounding a curve, the bolt 25 will be moved, the amount being determined by the position of the lock nut 21, to permit oil to run down the threads of the bolt and be deposited on the wheel flange. By proper manipulation of the lock nut 21 a sufficient 30 amount of oil is delivered to the wheel to permit proper lubrication thereof and at the same time acting to prevent the delivery of a quantity of oil which might interfere with the operation of the locomotive because of 35 slipping and the like. The resilient or yieldable mounting 13 between the frame and the casing 12 will permit a sufficient amount of play between the locomotive and frame without causing the bolt to open the 40 valve unduly. However, it is such as not to interfere with the opening of the valve whenever there is sufficient relative movement between the wheel and the frame as occasioned when rounding curves and the 45 like.

I am aware that modifications of such a device are possible and such modifications I intend to include as coming within the scope of the appended claims.

50 I claim:—

1. In combination, a lubricator container flexibly connected to an engine frame for

movement relative thereto, and a rigid member projecting from the container engaging a wheel flange and operable thereby to permit oil to flow from the container. 55

2. In combination, an oil container flexibly mounted adjacent a wheel and having an oil outlet, and a gravity valve controlling said outlet, said valve having a stem projecting in the path of said wheel and operable thereby on bodily movement thereof to open said outlet. 60

3. In combination, a wheel, an oiler having a valve controlled outlet, a gravity valve 65 having a threaded stem operatively associated with the wheel, and means including a nut on the stem for regulating the amount of the oil delivered.

4. In combination, a wheel, and an oiler 70 having a valve controlled outlet, and an associated gravity valve having a stem engaging the wheel for operating the valve.

5. In combination a wheel, an oiler having a valve controlled outlet and an associated valve having a stem provided with threads 75 for engaging the wheel and conducting oil thereto.

6. In combination, a wheel, an oiler having a valve controlled outlet, an associated valve having a stem provided with threads 80 for engaging the wheel and conducting oil thereto, and a nut on said stem for regulating the movement of the valve with respect to the outlet. 85

7. In combination, a wheel, an oiler having a valve controlled outlet, an associated valve including a bolt loosely fitting in said outlet, the head of said bolt serving to close said outlet, and the stem of the bolt serving 90 to conduct oil to said wheel.

8. In combination, a wheel, an oiler having a valve controlled outlet, an associated valve including a bolt loosely fitting in said outlet, the head of said bolt serving to close 95 said outlet, and the stem of the bolt serving to conduct oil to said wheel, and a nut on said bolt to control the flow of oil through said outlet by limiting the movement of said bolt therein. 100

Signed at Joliet, State of Illinois, this 21st day of March, A. D., 1918.

JAMES W. FOX.
